UNITED STATES PATENT OFFICE

SWAN E. NORD AND RAYMOND M. MIILU, OF SEATTLE, WASHINGTON, ASSIGNEES TO STANDARD OIL COMPANY OF CALIFORNIA, OF SAN FRANCISCO, CALIFORNIA, A COR-PORATION OF DELAWARE

DESIGN FOR A LIQUID DISPENSER

Application filed September 28, 1932. Serial No. 45,105. Term of patent 3½ years.

To all whom it may concern:

Be it known that we, SWAN E. NORD and RAYMOND M. MIILU, citizens of the United States, both residing in the city of Seattle, county of King, State of Washington, have invented a new, original, and ornamental Design for a Liquid Dispenser, of which the following is a specification, reference being had to the accompanying drawing, forming part thereof.

In the drawing Figure 1 is a perspective view, Figure 2 is a side elevation and Figure 3 is a top plan view of a liquid dispenser showing our new design, the fittings being omitted.

We claim:

The ornamental design for a liquid dispenser, as shown and described.

Signed at Seattle, Washington, the 19th day of September, 1932.

SWAN E. NORD.
RAYMOND M. MIILU.
